FLOATING CEILING FOR CAR ROOFS

William D. Thompson, Birmingham, Mich., and
William E. Bikle, Park Ridge, Ill., assignors to
Chicago-Hutchins Corporation, Chicago, Ill., a
corporation of Delaware

Application May 3, 1937, Serial No. 140,486

8 Claims. (Cl. 108—5.2)

The invention relates to car roofs of the so-called two-plane type, in which the use of independent carlines is dispensed with and the sheets are secured to each other by abutting vertically extending flanges embraced by seam caps and riveted to each other. It is the object of the invention to provide such type of roof with a floating ceiling which will prevent the dropping of moisture condensation from the roof and will also form a thermal insulation. It is a further object to provide a construction which permits of readily securing the floating ceiling after the completion of the roof proper and the riveting of the sheets to each other and to the seam caps. To this end, the invention consists in the construction and method of assembling the same as hereinafter set forth.

In the drawings:

Figure 1 is a cross section through a portion 20 of a car having a roof of the type above described showing the manner of securing the floating ceiling thereto;

Figure 2 is a plan view of a portion of the roof;

Figure 3 is a longitudinal section on line 3—3 25 of Figure 2 through both the roof and ceiling;

Figure 4 is an elevation of the hanger strip removed;

Figure 5 is a cross section at the ridge showing the manner of floatingly supporting the ceiling panels on opposite sides thereof;

Figure 6 is a sectional plan view on the line 6—6 of Figure 7;

Figure 7 is a longitudinal section on line 7—7 of Figure 5;

Figure 8 is a section showing a portion of Figure 3 on an enlarged scale.

The roof is formed of a series of roofing sheets A, preferably extending from eaves to eaves, each sheet having an upper plane portion A' in the center thereof and lower plane portions A² on opposite sides terminating in upwardly extending flanges A³ which abut against the corresponding flanges of adjacent sheets. The flanges A³ are embraced by a seam cap B, preferably having foot flanges B' which bear against a slightly upwardly offset portion A⁴ at the margins of the sheets. A series of rivets C secure these seam caps and the embracing flanges to each other.

To secure a floating ceiling to this type of roof, hanger strips D are secured at the seams to extend from ridge to eaves and downward below the lower plane portion A² of the roof. These strips are then provided with angle flanges D' bent to extend laterally and alternately upon opposite sides of the strip. Ledge strips E, pref-

erably of wood, are secured by screws F to these laterally extending flanges and form marginal supports for the ceiling panels G, which are thus held slightly below the lower plane portions A² of the roof. The strips D could be placed 5 between the flanges A³ of adjacent roofing sheets and secured thereto by the same rivets C which secure these flanges to each other and to the seam caps B. This, however, would necessitate assembling the ceiling simultaneously with the 10 assembling of the roofing sheets and would render it difficult to remove the ceiling panels without injury to the roof. This difficulty is overcome by the following construction:

When the roofing sheets are assembled, strips 15 H of the same or slightly greater thickness than the strips D, are placed between the flanges A³ and are secured thereto by the rivets C which also attach the seam caps B. The strips H are cut away at points so as to leave spaces between the flanges A³ for the insertion of portions of the strips D. As shown, the strips D have upwardly extending ears D² and D³ adjacent to opposite ends thereof which are so positioned as to register with the spaces formed 20 between sections of the strips H and to also register with one of the rivets. Thus when the roof is assembled the sheets A, seam caps B, and strips H are riveted to each other, but the rivet holes which register with the ears D³ are 25 omitted. The ceiling may then be secured to the roof by successively placing the strips D in position with the ears D² and D³ thereof inserted in the spaces between the flanges A³ of the sheets. These strips are then secured by 30 the insertion of rivets C' through the unfilled apertures in the seam cap and flanges A³ and also through registering apertures D⁴ in the ears D² and D³.

The ceiling panels G may be of any suitable 40 construction, but as shown, are formed of ply board. The dimensions of the panels are such as to fit between the strips D with a slight clearance so as to permit of a limited independent movement of said panels with respect to the 45 roof. The ledges formed by the strips E support the panels from downward displacement, and to prevent them from jumping upward spacer blocks I² are secured at intervals to the margins thereof. These spacer blocks bear against 50 the under faces of the upwardly offset portions B' of the sheets and hold the panels G slightly spaced from the under face of the lower plane portions A².

For supporting the ceiling panels on opposite 55

sides of the ridge, we preferably provide the following construction:

I is a hanger member which is secured at the ridge between the seam flanges of adjacent sheets 5 and depending therefrom, is provided with a laterally extending flange I'. To this flange is secured a longitudinally extending member J mortised at J' to form supporting bearings for the panels upon opposite sides of the ridge, this also 10 providing sufficient clearance for the floating action. One method of securing the member J to the flange I' is shown in Figures 6 and 7 in which K is a flange secured to the flange I' to extend to the opposite side of the member I. 15 L and L' are bayonet slots formed in the member K on one side and in the members I' and K upon the opposite side of the member I. These slots have entrance portions on opposite sides respectively of the center of the ridge, and portions extending laterally therefrom slightly past the center of the ridge. This permits of engaging headed bolts M with these slots and moving them to a position in alignment with each other at the center of the ridge. The member J may then 20 be attached to the hanger by means of these bolts and preferably said member J is formed of a series of short sections J, J' which abut each other in the plane of the hanger, each section being secured by one of the bolts. Thus the 25 structure is one which facilitates the installation of the ceiling after the construction of the car roof.

What we claim as our invention is:

1. The combination with a car roof comprising 30 a series of roofing sheets with adjacent flanges riveted to each other and with provision for a downwardly opening space between said flanges at one or more points, of a strip provided with an upwardly extending ear insertable into said space 35 after the roof is assembled, a rivet for securing said ear to said flanges, and a ceiling panel supported on said strip.

2. The combination with a car roof comprising 40 a series of roofing sheets with abutting flanges rigidly secured to each other, of a spacer between said flanges interrupted at one or more points to leave a downwardly opening space between said flanges, a strip provided with an upwardly extending ear for insertion in said space, means 45 for securing said ear to said flanges, and a ceiling panel supported on said strip beneath said roof.

3. The combination with a car roof comprising 50 a series of roofing sheets with adjacent upwardly extending flanges, and a seam cap for covering said flanges, of a spacer between said flanges interrupted to leave a downwardly opening space between said flanges, a strip having an ear for engaging said downwardly opening space, rivets for rigidly securing said seam cap, flanges and spacer to each other, a rivet for securing said ear to said flanges in the space therebetween, and a ceiling panel supported on said strip.

4. The combination with a car roof comprising 60 a series of roofing sheets with adjacent upwardly extending flanges, and a seam cap for covering said flanges, of a spacer between said flanges interrupted at a plurality of points to leave downwardly opening spaces between said flanges, a strip having upwardly extending ears for engaging said downwardly opening spaces, rivets for securing said seam cap, flanges and spacer to each

other, rivets for securing said ears to said flanges when in the spaces therebetween, and a ceiling panel supported on said strip.

5. The combination with a car roof comprising 5 a series of roofing sheets with adjacent upwardly extending flanges, and a seam cap for covering said flanges, of a spacer between said flanges interrupted at a plurality of points to leave downwardly opening spaces between said flanges, a strip having upwardly extending ears for engaging said downwardly opening spaces, and provided at its lower edge with alternately oppositely extending angle flanges, rivets for securing said seam cap, flanges and spacer to each other, rivets for securing said ears in the spaces between said strips, ledge strips secured to the flanges on the opposite sides of the aforesaid strip, and ceiling panels supported on said ledge strips. 10 15

6. The combination with a car roof comprising 20 a series of roofing sheets with adjacent flanges riveted to each other with a space therebetween in the ridge portion, of a hanger strip at the ridge inserted between said flanges and secured thereto, said strip depending below said sheets and provided with a laterally extending flange, a strip extending longitudinally beneath the ridge secured to said flange and rabbeted on its opposite edges, and ceiling panels on opposite sides of the ridge engaging said rabbeted edges and supported on said strip. 25 30

7. The combination with a car roof comprising 35 a series of roofing sheets with adjacent flanges riveted to each other with a space therebetween in the ridge portion, of a hanger strip at the ridge inserted between said flanges and secured thereto, said strip depending below said sheets and provided with a laterally extending flange, a bayonet slot in said flange having an entrance portion upon one side of the center of the ridge and a portion extending laterally slightly beyond the ridge, a headed bolt for engaging said slot to be positioned at the center of the ridge, a longitudinally extending strip beneath the ridge secured to said flange by said bolt, said strip being rabbeted on opposite edges thereof, and ceiling panels on opposite sides of the ridge engaging said rabbeted edges and supported on said strip. 40 45

8. The combination with a car roof comprising 50 a series of roofing sheets extending upon opposite sides of the ridge with adjacent flanges riveted to each other and with a space therebetween in the ridge portion, of a hanger strip at the ridge inserted between said flanges and secured thereto, said strip depending below said sheets and having laterally extending flanges on 55 opposite sides thereof, said flanges having bayonet slots therein with entrance portions on one side of the center of the ridge and portions extending laterally therefrom slightly beyond the ridge, aligned strips extending beneath the ridge and abutting against each other in the plane of said hanger, said strips being rabbeted along their opposite edges, bolts for securing said aligned strips to said flanges, said bolts being entered through said slots and positioned in alignment with each other at the ridge, and ceiling panels engaging the rabbeted edges of said strips on opposite sides of the ridge. 60 65
